[57] CLAIM

The ornamental design for an ashtray, as shown and described.

DESCRIPTION

FIG. 1 is a front elevational view of the ashtray according to the design of the present invention;
 FIG. 2 is a left side elevational view thereof;
 FIG. 3 is a right side elevational view thereof;
 FIG. 4 is a rear elevational view thereof;
 FIG. 5 is a top plan view thereof;
 FIG. 6 is a bottom plan view thereof;
 FIG. 7 is a front top perspective view thereof;
 FIG. 8 is a bottom perspective view thereof;
 FIG. 9 is a top plan view thereof, with the cover portion shown for clarity of illustration only;
 FIG. 10 is a bottom plan view of the cover portion of the ashtray;
 FIG. 11 is a front elevational view of the cover portion of the ashtray;
 FIG. 12 is a front top perspective view of the cover portion of the ashtray;

FIG. 13 is a bottom perspective view of the cover portion of the ashtray;

FIG. 14 is a top perspective view of the ashtray with the cover removed; and,

FIG. 15 is a central longitudinal cross sectional view of the ashtray with the cover removed.
